UNITED STATES PATENT OFFICE.

CHARLES D. CARTER, OF NEW YORK, AND GEORGE F. BIBB, OF TROY, NEW YORK,
ASSIGNORS TO THE FLOYD-WELLS COMPANY, OF ROYERSFORD, PENNSYLVANIA,
A CORPORATION OF PENNSYLVANIA.

OVEN FOR COAL AND GAS STOVES.

1,211,916.

Specification of Letters Patent. Patented Jan. 9, 1917.

Application filed October 3, 1916. Serial No. 123,502.

To all whom it may concern:

Be it known that we, CHARLES D. CARTER, a citizen of the United States, residing in the city, county, and State of New York, and 5 GEORGE F. BIBB, a citizen of the United States, residing at Troy, in the county of Rensselaer, State of New York, have invented a new and useful Oven for Coal and Gas Stoves, of which the following is a specification.

Our invention consists of the provision of the oven of a stove for coal or any other fuel, known as a coal stove which can be heated on the principle of a gas stove, and ventilated to remove in season the products of combustion from the gas burner.

The invention is satisfactorily illustrated in the accompanying drawing, but the important instrumentalities thereof may be varied, and so it is to be understood that the invention is not limited to the specific details shown and described.

Figure 1 represents a vertical section of a portion of a coal and gas stove embodying 25 our invention. Fig. 2 represents a similar view showing a member thereof in a different position from that shown in Fig. 1. Fig. 3 represents a bottom plan view of the rack of the oven and the base plate thereof. 30 Similar numerals of reference indicate corresponding parts in the figures.

Referring to the drawings, 1 designates the oven of a stove, and 2 the combustion chamber of the latter for coal or other fuel, 35 whereby said oven is heated in usual manner.

In the floor of the oven is the opening 3 from the wall of which depends the flue or casing 4 which is open at the top, and has 40 air inlets at the bottom, said flue containing the gas burner 5 which is provided with the supply pipe 6, it being noticed in Fig. 1, that the products of combustion from said burner are adapted to pass through said opening 3 from said flue or passage 4 and so enter the oven. The central portion of the floor of 45 the oven has a depressed rim 7 which forms the seat for the baffle plate 8, which is adapted to close the opening 3 when it is not desired to employ the gas burner 5 for heating the oven 1, the gas in such case being cut off, said baffle plate 8 being formed of a piece 50 of suitable metal or material from which depends the stem or hanger 9, which passes

through the opening 3 and is adapted to be 55 raised and lowered by any desirable means, as for instance, those shown in a prior application for patent, filed by us on the sixth day of May, 1916, Serial No. 95,778, it being evident that when said baffle plate is 60 raised, the opening 3 is uncovered when the oven may be heated by the gas burner 5, the products of combustion then passing through said opening into the burner. It is requisite at times to remove said products of combustion from the oven, especially when the latter highly fills the same and it is desired to refresh the oven with new supplies of products of combustion, or in other words, to ventilate the oven by providing for the escape of the products of combustion that have 65 filled the oven. To accomplish this we form in the rim or seat 7, the ports 10, and connect with the portion of the stove below and at the side of the oven the flue 11, said ports 70 forming communications for the oven with said flue, said communications existing when the baffle plate is raised, as in Fig. 1. Then the ports 10 are uncovered by said plate as raised and the products of combustion from 75 the gas burner after circulating in the oven find an exit through the ports 10, as shown by the short arrows Fig. 1, into the flue 11, which latter leads from the stove to a chimney, the effect of which is evident.

12 designates a rack for the oven, the same being open or grated as usual, and which excepting the features of our invention applied thereto, is of usual construction, it being supported on ledges 13 on the sides of 80 the oven. Bolted or otherwise connected with the underside of said rack and depending therefrom is the deflector 14, which has vertical perforations 15 therethrough, it being separated from the rack forming the hot 85 air space or chamber 16. It will be seen that the hot air entering the oven impinges said deflector whereby some of the hot air passes through the side portions of the rack, and some passes in many currents through the 90 perforations 14 of the deflector into the chamber 16, and from thence to the bottom of the rack and through the latter and above the same and returning to the bottom of the oven, causing a thorough circulation 95 of hot air in the entire oven, thus effectively baking or roasting the food on the rack without burning the bottom of the same.

The rack forms the subject matter of another application of even date of filing.

Having thus described our invention what we claim as new and desire to secure by Letters Patent, is:-

- 5 1. In a stove oven of the character stated having a flue for the products of combustion from the stove, the bottom of said oven having therein an opening, a casing depending from said bottom in communication with said opening, a gas burner in said casing and a movably mounted baffle plate adapted to close said opening, said bottom having therein a port affording communication between 10 the oven and said flue, said port being covered by said plate when in its closed position.
- 15 2. A stove oven of the character stated having its bottom wall formed with an opening with a depressed portion around said opening provided with a port, a casing depending from said wall at said opening, a gas

burner in said casing, said port being outside said casing, a flue communicating with the combustion chamber of the stove, and a movable plate fitted to said opening adapted to be seated on said portion and to cover said port.

- 20 3. In a stove oven of the character stated, a depending casing in communication with said oven, a gas burner in said casing, a flue for the products of combustion from the stove, and a movable baffle plate adapted to open and close the communication between said casing and the oven, said bottom having therein a port adapted to be covered by said baffle plate when in its closed position.
